(57) CLAIM

The ornamental design for the display with butterfly folding stand, as shown and described.

DESCRIPTION

FIG. 1 is a rear perspective view of a display with butterfly folding stand showing our new design;
FIG. 2 is a front view thereof;
FIG. 3 is a rear view thereof;
FIG. 4 is a left side view thereof;
FIG. 5 is right side view thereof;
FIG. 6 is a top plan view thereof;
FIG. 7 is a bottom plan view thereof;
FIG. 8 is a rear reference perspective view thereof showing the state that the folding stand has been closed; and,
FIG. 9 is a front perspective view thereof.
The broken lines in the drawings are for illustrative purposes only and form no part of the claimed design.
